US00D773534S

(12) United States Design Patent (10) Patent No.: US D773,534 S
(45) Date of Patent: * Dec. 6, 2016

(54) DISPLAY SCREEN OR PORTION THEREOF WITH ICON

(71) Applicant: Samsung Electronics Co., Ltd., Suwon-si (KR)

(72) Inventors: Seungju Yuk, Seoul (KR); Sookkyung Lee, Seoul (KR)

(73) Assignee: SAMSUNG ELECTRONICS CO., LTD., Suwon-Si (KR)

() Term: 15 Years

(21) Appl. No.: 29/529,093

(22) Filed: Jun. 3, 2015

(30) Foreign Application Priority Data

Feb. 27, 2015 (KR) 30-2015-0010369

(51) LOC (10) Cl. 14-04

(52) U.S. Cl.

USPC D14/495

(58) Field of Classification Search

USPC D14/485-495

CPC .. G06F 3/0482; G06F 3/0488; G06F 3/04817;

G06F 3/04883; G06F 3/04842
